CLAIM

The ornamental design for a network access point (NAP) enclosure, as shown and described.

DESCRIPTION

FIG. 1 is a front, top, right side perspective view of a network access point (NAP) enclosure;

FIG. 2 is a rear, bottom, left side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is top plan view thereof;

FIG. 8 is bottom plan view thereof; and,

FIG. 9 is the rear, bottom, left side perspective view of FIG. 2 with environment shown in broken lines.

The broken lines in the drawings depict portions of the network access point (NAP) enclosure that form no part of the claimed design.

The three concentric circles to the left of the term “PPC” in which the individual letters are connected forming part of the disclosure is a registered trademark of PPC BROADBAND, INC.
